DESCRIPTION

FIG. 1 is a top perspective view of a memory card, on a slightly reduced scale;

FIG. 2 is a bottom perspective view thereof, on a slightly reduced scale;

FIG. 3 is a top view thereof;

FIG. 4 is a first side view thereof;

FIG. 5 is a front view thereof;

FIG. 6 is a rear view thereof;

FIG. 7 is a bottom view thereof; and,

FIG. 8 is a second side view thereof.

The broken line drawings of pins on FIGS. 2 and 7 are for illustrative purposes only and form no part of the claimed design.
